UNITED STATES PATENT OFFICE.

RUDOLPH BECKER, OF ROSELLE PARK, NEW JERSEY, ASSIGNOR TO THE SINGER MANUFACTURING COMPANY, A CORPORATION OF NEW JERSEY.

HAT-SWEAT AND METHOD OF ATTACHMENT.

1,281,123.

Specification of Letters Patent.

Patented Oct. 8, 1918.

Application filed February 14, 1918. Serial No. 217,052.

To all whom it may concern:

Be it known that I, RUDOLPH BECKER, a citizen of the United States, residing at Roselle Park, in the county of Union and

5 State of New Jersey, have invented certain new and useful Improvements in Hat-Sweats and Methods of Attachment, of which the following is a specification, reference being had therein to the accompanying drawings.

10 This invention relates to head coverings and particularly to sweat bands for straw hats and their method of attachment.

In a companion application Serial No. 217,051, filed February 14, 1918 contemporaneously with this application, a hat having

15 a sweat band attached to it in a certain manner is fully described and claimed. This application is for different species of the inventions therein claimed broadly. As the

20 problem and its solution were fully explained in the said contemporaneously filed application it is deemed to be sufficient to but briefly state the problem and solution in this application.

25 A leather sweat band is commonly stitched to straw hats at the present day by first stitching the leather to a piece of cambric to form the "hat-sweat" and subsequently stitching the hat and cambric only together

30 to fasten the "hat sweat" in position at the junction of the brim and crown. By reason of the fact that the stitching of the hat and "hat sweat" together is done when the leather has been folded back over the stitches

35 uniting its lower edge to the cambric, the stitches uniting the hat sweat to the hat body were generally located about an eighth of an inch above the lower edge of the leather sweat. These uniting stitches are

40 concealed when the leather is afterward folded back into the hat.

The above described prevailing method was found to be objectionable because in the completed hat the lower edge of the sweat

45 band often stood away from the junction of the brim and crown leaving a gap or space presenting an unsightly appearance. It was also found that hats of a given size, seven for instance, would not fit uniformly for the

50 reason that the operators were unable in stitching the hat sweat in place to manipulate the same so as to compensate for the invariable variations in hat bodies which had been glued and blocked and were supposed to be size seven hat in the rough.

In the present invention the essential steps

of the prevailing practice have been pursued in the reverse order, *i. e.*, an anchor member or strip corresponding to the cambric of the old practice is first stitched to the hat and then the leather sweat band is stitched to the anchoring member, care being taken to do this in such a manner that a soft edge or ridge of needle penetrable material is substantially fixed in position at the junction of the brim or crown of the hat and as near the plane of the under surface of the finished brim as is practicable.

60 The object of this invention has been to improve the machine process of attaching sweat bands to straw hats having separately formed upper and under brims and to better the character of the product.

65 Over the invention disclosed in the companion and contemporaneously filed application the product is improved by reason of the secure fixing of the anchoring member or strip carrying the soft edge or ridge of material between the brims and at their junction with the crown portion of the hat and the process is specifically different.

70 In the accompanying drawings the article and successive steps in its formation are illustrated. Figure 1 shows a hat in perspective partially broken away to disclose its construction. Figs. 2 to 5 inclusive disclose successive steps or operations in the preferred method of construction. Figs. 6 to 9 inclusive disclose successive steps in a modified method of constructing the hat. Figs. 95 10 to 14 inclusive disclose an anchoring member having a corded soft edge or ridge. Figs. 15 and 16 show an anchoring member in which a soft edge or ridge is formed by folding a strip of suitable material. Fig. 17 95 illustrates on an enlarged scale the relative location of seams securing a hat sweat to a hat body. Figs. 18 and 19 show how an anchoring member may be incised or notched for convenience in folding.

100 The hat illustrated is of the type in which an under brim 1 is made separately from the upper brim 2 which is made in one operation with the crown 3 as is well known to those skilled in the art.

105 An anchoring member or strip of suitable material penetrable by a needle is secured between the upper and under brims 1 and 2 with a soft edge or ridge substantially in position at the junction of the brim portions and the crown. This may be done by longitudinally folding a strip between its edges

so as to dispose portions 4 and 5 of the width thereof at an angle with their junction or union 6 defining the desired soft edge or ridge of material located at the junction of the brim and crown. The portion 4 of the strip if cut on the straight may be incised or notched as indicated radially as frequently as is desired and to any suitable depth to facilitate the angular formation of the strip. 5

10 Preferably, however, the anchoring member or strip is made of bias cut fabric adapted to be distended or blocked to the desired angular formation in a variety of ways well known to those acquainted with the art.

15 The strip is secured to one of the brims, preferably the under brim, during its formation for example when the braid is being stitched, or if desired after the brim has been formed. The stitches securing the 20 strip to the brim are indicated at 7 and are preferably made on a machine. Obviously, however, the strip may be attached to both the under and upper brims after they have been formed either by a row of stitches as 25 indicated at 7' in Fig. 8 or by gluing or pasting the portion 4 of the strip between the upper and under brims and in either of these cases before or after stitching the brims together in a customary well known 30 manner at their outer edges as indicated by the seam 8, which seam 8 also serves to hold a narrow braid of straw 9 in place at the outer periphery of the brim. These operations are indicated diagrammatically in 35 Figs. 2, 3 and 4.

It is preferred to then stitch the portion 5 of the strip to the crown as indicated by the seam shown at 10, but this is not necessary and may be omitted or may be accomplished or 40 in another way, as for instance by gluing or pasting the portion 5 of the strip flat against the crown of the hat.

The second broad essential step in the process is the attachment of a leather sweat- 45 band 11 to the soft edge or ridge 6 of the strip by a suitable nice appearing seam 12 such as a single-thread overedge chain-stitch. This second essential step is indicated in Fig. 5 and is preferably performed 50 with the leather in substantially the position it occupies in the finished hat enabling the operator to scrutinize the appearance of the work during its progress to completion and to manipulate it with greater freedom than 55 in the prevailing method.

In Figs. 6-9, inclusive, a slightly different modification of the above described method is shown diagrammatically. It differs therefrom in this respect, that the strip 60 4'-5' is not folded until after it is secured between the brims, the portion 5', if not of bias material, being slit or notched radially to approximately the junction of the brim and crown in order to permit folding of the 65 strip back against the crown of the hat

which folding occurs preferably before the sweat-band is stitched to the soft edge or ridge of the strip. The strip 4'-5' is also shown secured to both brims by a seam 7'. This is the preferred method of construction 70 for with bias cut material the anchoring member may be stitched as at 7' and then readily bent into angular form.

The soft edge or ridge 6 may be increased or thickened in size and a more ornamental 75 appearance given to the finished hat by securing a cord or braid 13 of suitable material at the edge or ridge portion 6 of the anchoring member. This may be done in a variety of ways obvious to those skilled in 80 the art and some of the possible forms of a corded edge are shown in Figs. 10 to 14, inclusive, in each of which figures the cord 13 is shown secured in place by stitches 14 either passing directly through the cord or 85 serving to form the strip into a casing enclosing the cord. In Fig. 17 a corded edge is disclosed in an enlarged cross-section and illustrates the relative location of the several 90 seams which may be used to secure a sweat-band to a straw hat by the method of the present invention.

In Figs. 15 and 16 still other forms of a soft edge or ridge are shown. In Fig. 15 a strip is shown folded longitudinally at 16 95 and in Fig. 16 a strip is shown hemmed or rolled on one edge as indicated at 17. These forms of the soft edge or ridge are substantially fixed in an accessible position at the junction of the brim and crown as in the 100 preferred form, the major or body portion of the anchoring member however lying entirely between the brims. No portion of these two forms of a strip lies flat against the crown of the hat. 105

In this application, as in the contemporaneously filed application Serial No. 217,051 it is to be noticed that the nice appearing seam 12 securing the leather sweat-band 11 to the soft edge or ridge, occupies a portion 110 or zone of the anchoring member entirely outside and independent of that occupied by the stitches 7 or 7' and 10 securing the anchoring member or strip to the body of the hat. The seam 12 may be made on the machine disclosed in said contemporaneous application. 115

The anchoring member may as before stated be made of bias cut fabric such as cambric or it may be made of felt which 120 could be given the desired form in a variety of ways.

Having thus set forth the nature of the invention, what I claim herein is:—

1. A straw hat having united upper and 125 under brims, a strip of material anchored between the upper and under brims and presenting a ridge at the inside periphery of the brim, and a sweat-band having its lower edge stitched to said ridge. 130

2. A straw hat having united upper and under brims, a strip of material anchored between the upper and under brims and presenting a corded edge at the inside periphery 5 of the brim, and a sweat-band having its lower edge stitched to said edge.
3. In a straw hat having united upper and under brims, a strip of material having two angularly disposed portions, one of which 10 portions is secured between the upper and under brims, and the other of which is secured to the inside of the crown of the hat, and a sweat-band stitched at its lower edge to the junction of the angularly disposed 15 portions of the strip.
4. A straw hat having united upper and under brim portions, a strip of material having a cord secured thereto intermediate its side edges and extending lengthwise thereof, 20 the strip between one of its edges and the cord being secured between the upper and under brims and between the other of its edges and the cord being disposed adjacent the vertical walls of the hat crown, and a 25 sweat-band secured by stitches at its lower edge to the cord of the strip.
5. A straw hat having united upper and under brims a strip of material having a thickened soft edge adjacent the inner periphery of the brims and secured between the upper and under brims, and a sweat-band having its lower edge stitched to the thickened soft edge of the strip.
6. The process of attaching sweat-bands 30 to straw-hats having separately formed upper and under brims, the former of which is made in one operation with the crown including, securing a strip of material between the brims with an anchoring portion 35 accessibly arranged at the junction of the brim and crown portions, securing the brims together, and stitching a sweat-band to the accessible anchoring portion of the strip.
7. The process of attaching sweat-bands to straw-hats having separately formed upper and under brims, the former of which is made in one operation with the crown including, forming a strip with a ridge of soft material, securing the strip between the 40 brims with the ridge of soft material accessibly arranged at the junction of the brim and crown, securing the brims together, and stitching a sweat-band to the accessible soft edge of the strip.
8. The process of attaching sweat-bands to straw-hats having separately formed upper and under brims, the former of which is made in one operation with the crown including, securing a cord to a strip of material by stitches, securing the strip between the brims with the cord at the junction of the brim and crown, securing the brims together, and stitching a sweat-band to the corded portion of the strip.
9. The process of attaching sweat-bands 45 to straw-hats having separately formed upper and under brims, the former of which is made in one operation with the crown including, securing a strip of material anchored between the upper and under brims, the former of which is made in one operation with the crown including, securing a strip of material to one of the brims during its formation with an 50 accessible portion of the strip located at the junction of the brim and crown, securing the brims together, and stitching a sweat-band to the accessible portion of the strip.
10. The process of attaching sweat-bands to straw-hats having separately formed upper and under brims, the former of which is made in one operation with the crown including, securing a cord by stitches to a strip throughout its length, securing the strip to one of the brims with the cord located adjacent the junction of the brim and crown, securing the brims together, and stitching a sweat-band to the free edge of the strip.
11. The process of attaching sweat-bands to straw-hats having separately formed upper and under brims, the former of which is made in one operation with the crown including, securing a strip to the under brim with an accessible portion thereof located adjacent the junction of the brim and crown, securing the brims together, and stitching a sweat-band to the accessible portion of the strip.
12. The process of attaching sweat-bands to straw-hats having separately formed upper and under brims, the former of which is made in one operation with the crown including, securing a cord by stitches to a strip throughout its length, securing the strip to the under brims with the cord located adjacent the junction of the brim and crown, securing the brims together, and stitching a sweatband to the corded portion of the strip.
13. The process of attaching sweat-bands to straw-hats having separately formed upper and under brims, the former of which is made in one operation with the crown including, securing a strip of material to one of the brims during its formation with an accessible portion of the strip located at the junction of the brim and crown, securing the brims together, and stitching a sweat-band to the accessible portion of the strip.
14. The process of attaching sweat-bands to straw-hats having separately formed upper and under brims, the former of which is made in one operation with the crown including, securing a strip of material to the under brim during its formation with a portion of the strip at the junction of the brim and crown, securing the brims together and stitching a sweat-band to the said portion of the strip.
15. The process of attaching sweat-bands to straw-hats having separately formed upper and under brims, the former of which is made in one operation with the crown including, securing a cord to a strip by stitches, securing the strip to one of the brims during

its formation with the cord at the junction of the brim and crown, securing the brims together, and securing the sweat-band by stitches to the corded portion of the strip.

5 16. The process of attaching sweat-bands to straw-hats having separately formed upper and under brims, the former of which is made in one operation with the crown including, securing a cord to a strip by 10 stitches, securing the strip to the under brim during its formation with the cord at the junction of the brim and crown, securing the brims together, and securing the sweat-band by stitches to the corded 15 portion of the strip.

17. The process of attaching sweat-bands to straw-hats having separately formed upper and under brims, the former of which is made in one operation with the crown including, securing a strip for a portion of its width between the upper and under brims during the formation of the hat with the rest of the width of the strip disposed within the internal periphery of the brims, 25 and subsequently stitching a sweat-band to the strip where it emerges from between the upper and under brims.

18. The process of attaching sweat-bands to straw-hats having separately formed upper and under brims, the former of which is made in one operation with the crown including, securing a strip for a portion of its width to one of the brims during its formation with the rest of the strip disposed

within the internal periphery of the brims, 35 securing the brims together, and subsequently stitching a sweat-band to the strip where it emerges from between the upper and under brims.

19. The process of attaching sweat-bands 40 to straw-hats having separately formed upper and under brims, the former of which is made in one operation with the crown including, securing a strip for a portion of its width to the under brim during its 45 formation with the rest of the strip disposed within the internal periphery of the brim, securing the upper and under brims together, and subsequently stitching the sweat-band to the strip where it emerges 50 from between the upper and under brims.

20. The process of attaching sweat-bands to straw-hats having separately formed upper and under brims, the former of which is made in one operation with the crown including, 55 securing a strip of bias fabric for a portion of its width between the upper and under brims during the formation of the hat body, subsequently positioning the rest of the width of the strip inside and against the crown of the hat, and subsequently stitching a sweat-band to the strip adjacent the junction of the brim and crown 60 of the hat.

In testimony whereof I have signed my 65 name to this specification.

RUDOLPH BECKER.
